Primary Examiner — Cynthia M. Chin(74) *Attorney, Agent, or Firm* — Andrew Kenny(57) **CLAIM**

The ornamental design for a dual-motor watercraft, as shown and described.

DESCRIPTION

FIG. 1 is a top perspective view of the dual-motor watercraft.

FIG. 2 is a top view of the dual-motor watercraft.

FIG. 3 is an exploded perspective view of the two components of the dual-motor watercraft, hull and insert; and, FIG. 4 is a section view of the dual-motor watercraft taken in the direction of line 4-4 in FIG. 2.

The broken lines are for the purpose of illustrating portions of the watercraft that form no part of the claimed design.

1 Claim, 4 Drawing Sheets(56)
